UNITED STATES PATENT OFFICE.

CURT GOLTDAMMER, OF KATTOWITZ, GERMANY.

GRINDING-MILL OR CRUSHER.

1,186,476.

Specification of Letters Patent.

Patented June 6, 1916.

Application filed July 31, 1915. Serial No. 43,026.

To all whom it may concern:

Be it known that I, CURT GOLTDAMMER, subject of the King of Prussia, residing at Kattowitz, Province of Silesia, Germany, 5 have invented certain new and useful Improvements in Grinding-Mills or Crushers, of which the following is a specification.

My invention relates to grinding mills or crushers used for reducing hard materials 10 such as ore, cement or the like to a coarse powder or to dust.

The invention relates more especially to that type of mills or crushers in which three or more steel rollers are encircled by a steel 15 ring coöperating with the rollers in the reduction of the material introduced between them. In mills of this kind the steel ring is usually carried and caused to rotate by the uppermost roller, while the lower rollers 20 are pressed against the inner surface of the ring by springs exerting an outward pull upon them. The rollers being encircled by the ring can not easily be laid open or removed for inspection and repairs. In order 25 to obviate this inconvenience, according to my invention the bearings of all the rolls are located in two separate frames placed on both sides of, but entirely separated from the mill proper and the casing surrounding 30 same.

The mill proper is not in any way connected with the means for carrying the roll axles and it is possible therefore to lay the mill open by simply removing the casing. 35 In order to facilitate this removal the casing is divided vertically, the two halves of the casing being adapted to be moved aside after the screws connecting them and fastening them to the base plate have been taken off, 40 without necessitating the use of a lifting device.

In the drawings affixed to the specification the preferred form of a mill according to the present invention is shown.

45 Figure 1 is a side elevation, partly in section; Fig. 2 is a front elevation, partly in vertical cross-section; Fig. 3 is a cross section on the line 2—2 (Fig. 2), partly broken away, with the two halves of the casing 50 pulled aside (Figs. 3^a and 3^b).

z is the base plate, a a are two frames or trusses carried by said plate and located at both sides of the mill proper. The axle b₁ of the upper grinding roller w₁ is carried 55 in bearings p₁ in the frames, said bearings being either stationary, as represented in the

drawings, or movable against the action of suitable springs. The axles b₂ b₃ of the two lower rollers w₂ w₃ are carried in bearings p₂ p₃ suspended on the frames a by aid of 60 levers d pivoted to pins v located on the outer side of the frames. Connecting rods f connected with the axle bearings p₂ p₃ by knuckle joints y formed in extensions j of levers d are acted upon in a radial direction by strong springs g inserted between 65 seats t on the frames and twin plates u₂ u₃ adapted to be adjusted on the connecting rods by aid of nuts u₁, a ball and socket joint u₄ being inserted between the plates. 70 By tightening the nuts u₁ the degree of compression of the springs g may be varied, said compression corresponding to the radial pressure exerted by the rollers w² w³ upon the ring r running freely upon the 75 rollers w₁ w₂ w₃ (Fig. 3). The rollers w₂ w₃ owing to their being suspended on the oscillating levers d and owing to the springs g are free to follow all radial movements occurring while the mill is working. Such 80 movements are further facilitated by the action of the joint u₄ and of link y. Provided that the levers d are broad enough and the axles b₂ b₃ are provided with suitable collars the rollers are also free to move axially to a certain extent. 85

In order to prevent the material to be ground from passing through the side openings in the walls of the mill for the passage of the roller axles, dish-shaped disks k₁ 90 are fastened to the rollers w₁, w₂, w₃ by means of bolts k, said disks being provided with oblique extending annular flanges k₂. This arrangement is preferable to the use of solid flanges in so far as the disks k₁ do not 95 come in contact with the grinding ring r nor with the hard material to be ground, while the rollers are rotating. The disks k₁ also serve to prevent bigger pieces of iron sometimes admixed with the material to be 100 ground from being jammed between the rollers and the side walls of the mill.

The driving pulley s is fixed on the axle b₁ of roller w₁. Ring r is carried along by the friction created between it and roller w₁. The rollers and the ring r are inclosed in a casing i consisting of two halves i₁ and i₂ (Figs. 3^a and 3^b). The two halves of the casing are not in any way connected with the axles b₁ b₂ b₃ nor with ring r either; in 110 the working position they are fastened to the base plate z by screws m₁, and to each

other by screws m_2 . The casing walls are provided with apertures i_3 i_4 i_5 i_6 allowing the axles b_1 b_2 b_3 to pass through. Part i_2 of the casing carries the feed funnel T terminating in two channels S_1 S_2 feeding the material to be ground sidewise between the lower roller w_3 and ring r at X . The ground material is removed from the mill through an aperture Q provided in the base 10 plate Z .

If it is desired to remove the inner parts, the screws m_1 m_2 are loosened and the halves i_1 i_2 of the casing are withdrawn sidewise. Now the nuts u_1 are removed from 15 the connection rods f and the covers from the bearings p_2 and p_3 . The bearings themselves will fall off the axles by themselves, thus allowing the axles to be withdrawn sidewise through the aperture of the trusses 20 a represented in Fig. 1, together with the rollers w_2 w_3 . If it is desired to remove the upper roller w_1 and ring r also, this latter should be lifted somewhat, in order to allow the upper axle b_1 and roller w_1 to be 25 moved, after taking off the cover of bearing b_1 . Ring r being thus laid free may then be withdrawn between the trusses. Provided that the axle b_1 of the upper roller is located in stationary bearings, as shown 30 in the drawings, a single pulley s will serve for driving the mill without causing the rollers to be pulled out of position by the one-sided pull exerted upon the axle b_1 , as is usually the case in mills driven from a 35 single pulley located sidewise, such pulling action causing the rollers to be worn out on one side more than on the other side.

In the mill described above the casing merely serves its natural purpose of inclosing the grinding ring and rollers and of thus preventing dust from being spread about. Apart from this reason the casing might as well be dispensed with, as it does not serve 40 for carrying any movable parts.

45 I claim:—

1. In a grinding mill, the combination of a plurality of grinding rolls, a grinding ring surrounding said rolls and supported by one

of them, means for rotating the supporting roll and thereby actuating the grinding ring, 50 and a casing for the grinding devices adapted to be assembled and removed independent of any adjustment of said ring or rolls.

2. In a grinding mill, the combination of a pair of parallel frames, a plurality of 55 grinding rolls mounted in bearings in said frames, a grinding ring surrounding the rolls and supported by one of them, means for driving the said supporting roll to rotate the grinding ring and other rolls, and a casing adapted to be positioned about or removed from the grinding devices independent of any adjustment of the grinding ring, the rolls or supporting frames.

3. In a grinding mill, the combination of 60 a pair of parallel frames, a plurality of grinding rolls mounted in bearings in said frames, a grinding ring surrounding the rolls and supported by one of them, means for driving the said supporting roll to rotate the grinding ring and other rolls, and a 65 sectional casing, inclosing the grinding devices, separable on a plane parallel to the axes of the rolls and adapted to be removed independently of any adjustment of the ring, 70 75 rolls or said supporting frames.

4. In a grinding mill, the combination of a suitable frame, an upper grinding roll mounted in relatively stationary bearings on the frame, levers pivoted on the frame below 80 and at opposite sides of the bearings for said upper roll, two grinding rolls mounted in bearings on said levers, a grinding ring surrounding all of the rolls and supported by the upper roll, means for revolving the 85 ring, and a casing inclosing the grinding devices and removable therefrom without any adjustment of the ring, rolls or bearings for the latter.

In testimony whereof I affix my signature 90 in presence of two witnesses.

CURT GOLTDAMMER.
